CLAIM

The ornamental design for a housing for an infrared signal detector, as shown and described.

DESCRIPTION

FIG. 1 is a top, front and left side perspective view of a housing for an infrared signal detector showing our new design;

FIG. 2 is a front elevational view thereof;

FIG. 3 is a right side elevational view thereof, the left side elevational view being identical;

FIG. 4 is a top plan view of the housing for an infrared signal detector, the bottom plan view being identical therewith; and

FIG. 5 is a rear elevational view thereof.
